(57) **CLAIM**

The ornamental design for a puck removal device, as shown and described.

DESCRIPTION

FIG. 1 is a referential front elevation view of a puck removal device;

FIG. 2 is a referential left hand elevation view of the design of FIG. 1;

FIG. 3 is a referential right hand elevation view of the design of FIG. 1;

FIG. 4 is a referential rear view of the design of FIG. 1;

FIG. 5 is a referential plan view of the design of FIG. 1;

FIG. 6 is a referential bottom view of the design of FIG. 1;

FIG. 7 is a referential front, top, right-side perspective view of the design of FIG. 1;

FIG. 8 is a referential rear, top, left-side perspective view of the design of FIG. 1; and,

FIG. 9 is a referential front, bottom, left-side perspective view of the design of FIG. 1.

Broken lines in the drawing, if included, depict portions of the puck removal device that form no part of the claimed design.

1 Claim, 9 Drawing Sheets
